UNITED STATES PATENT OFFICE.

EDWARD R. STETTINIUS, OF CHICAGO, ILLINOIS, ASSIGNOR TO THE
STIRLING COMPANY, OF SAME PLACE.

WATER-TUBE BOILER.

SPECIFICATION forming part of Letters Patent No. 669,774, dated March 12, 1901.

Application filed March 7, 1900. Serial No. 7,643. (No model.)

To all whom it may concern:

Be it known that I, EDWARD R. STETTINIUS, a citizen of the United States, residing at Chicago, in the county of Cook and State of Illinois, have invented a new and useful Improvement 5 in Water-Tube Boilers, of which the following is a specification.

The object of my invention is to improve the vertical water-tube boiler of the type commonly known as the "Stirling" boiler; and the invention consists in the features and combinations hereinafter described and claimed.

In the accompanying drawings, Figure 1 is a cross-section of one form of my improved boiler, one set of circulating-pipes being shown in dotted lines and outside the walls or setting and another set in full lines and inside the walls or setting; Fig. 2, a longitudinal sectional elevation of the boiler shown in Fig. 1; 20 Fig. 3, a cross-section of another form of my improved boiler, showing one set of circulating-pipes in dotted lines and outside the walls or setting and another set in full lines and inside the walls or setting; Fig. 4, a section in 25 elevation of the boiler shown in Fig. 3; and Fig. 5, the same as Fig. 4, except that one set of circulating-pipes is embedded in the walls or setting.

A, A', and A² are elevated steam and water drums, a pipes communicating between the steam-spaces thereof, and a' pipes communicating between the water-spaces thereof; B, lower mud-drums; C, banks of tubes connecting the elevated steam and water drums with the lower mud-drums; D, circulating-pipes communicating between the rear elevated steam and water drum and the front lower mud-drum; D', circulating-pipes communicating between the rear or middle elevated 35 steam and water drum and the rear lower mud-drum; E, the fireplace, and e a fire-brick arch over the same, and F fire-brick partitions in the rear of and adjacent to the front and middle banks of tubes.

The Stirling type of boiler, to which my invention relates, is so well known that I do not consider it necessary to describe its construction or operation in detail. In this view, and because they are clearly shown in the drawings, no description is considered necessary 50 of the elevated steam and water drums and

connecting-pipes, lower mud-drums, banks of tubes connecting the lower mud-drums with the elevated steam and water drums, fire-brick arches and partitions, and other features in common use as parts thereof. In addition to these parts or features, however, I provide one set of circulating-pipes D between the rear elevated steam and water drum and the front lower mud-drum and another 55 set of circulating-pipes D' between the rear or middle steam and water drum and the rear mud-drum. As shown, the pipes of the first set are outside the walls or setting or embedded therein, and the pipes communicate with 60 the ends of the drums to which they are attached, respectively; but their connections are not necessarily at the extreme ends of the drums, connection near the ends being sufficient. Any number of these pipes may be 65 used as desired, depending somewhat upon their size or diameter; but generally one at each end will be found sufficient, and sometimes a single pipe at one end only. As shown, the pipes of the second set are inside 70 the walls or setting and they connect through the shell of the drums to which they are attached, respectively. Any number of these pipes may be used as desired, and they may be placed in any desired position. 75

In filling, feed-water being introduced into the rear mud-drum passes up through the rear bank of tubes and the circulating-pipes D' into the rear steam and water drum in the form of boiler shown in Fig. 1 and into the 85 rear and middle steam and water drum in the form shown in Fig. 3, and from the rear steam and water drum it passes down through the circulating-pipes D to the front mud-drum and thence up through the front bank of tubes 90 to the front elevated steam and water drum in the form of boiler shown in Fig. 1, and up through the front and middle banks of tubes to the front and middle steam and water drums in the form shown in Fig. 3, and also 95 from the rear steam and water drum in the form of boiler shown in Fig. 1, and from the middle steam and water drum in the form shown in Fig. 3 through the connecting-pipes to the front steam and water drum. In operation, the front bank of tubes being in the hottest part of the boiler, the most rapid up- 100

ward circulation will be through this bank; but the circulating-pipes D permit a constant downflow and supply of water to take the place of water converted into steam in this 5 bank of tubes, and also the place of water passing from the front steam and water drum into the rear or middle steam and water drum or elsewhere. The water-spaces of the front and rear steam and water drums or front and 10 middle drums, as the case may be, communicating with each other, water passes from one of these drums to the other, as required by circulation and other conditions. In other 15 words, the circulating and connecting pipes provide for a powerful circulation of water up through the front bank of tubes and across from the front steam and water drum to the rear or middle steam and water drum, as the case may be, and down to the front 20 mud-drum, and so on in circuit, the practical effect being that the tubes of the front bank are more completely filled with cooler water or water free from steam and the transmission 25 of heat in this bank thereby greatly increased. 30 In addition to this primary circulation the water also flows from the rear or middle steam and water drum, as the case may be, back and down through the circulating-pipes D' to the rear mud-drum and up through the rear 35 bank of tubes to the rear steam and water drum, and so on in circuit. This latter circulation serves to heat the feed - water more uniformly and provides for a more complete separation and settlement of scale-forming 40 matter in the rear and cooler parts of the boiler. If feed - water be introduced in the rear or middle steam and water drum or elsewhere in the rear part of the boiler, the circulations will be practically unchanged. The 45 circulating - pipes being of larger diameter than the diameter of the tubes of the several banks and being located in a relatively cool part of the boiler provide for a constant and abundant supply of water from the rear part of the boiler to the front part, and this without having serious counter - currents in the tubes furnishing the heating-surface and primarily intended for the generation of steam.

I claim—

50 1. In a water-tube boiler, the combination of a plurality of elevated steam and water

drums, pipes communicating between the steam-spaces of said drums, pipes communicating between the water-spaces of the front steam and water drum and the steam and 55 water drum adjacent thereto, a front lower mud-drum, a rear lower mud-drum, a bank of tubes connecting the rear mud-drum with the rear steam and water drum, a bank or banks of tubes connecting the front mud-drum with the steam and water drum or drums having their water-spaces in communication, a circulating pipe or pipes at the 60 ends of and communicating between the rear steam and water drum and the front mud-drum, located in cool relation to the boiler-setting and giving an auxiliary circulation at the end between the two drums, a circulating pipe or pipes connecting the rear one of the steam and water drums having their water-spaces in communication with the rear mud-drum, means for introducing feed-water, and 65 means for drawing off steam, substantially as described.

2. In a water-tube boiler, the combination 70 of a plurality of elevated steam and water drums, pipes communicating between the steam-spaces of said drums, pipes communicating between the water-spaces of the front steam and water drum and the steam and 75 water drum adjacent thereto, a front lower mud-drum, a rear lower mud-drum, a bank of tubes connecting the rear mud-drum with the rear steam and water drum, a bank or banks of tubes connecting the front mud- 80 drum with the steam and water drum or drums having their water-spaces in communication, a circulating pipe or pipes communicating between the rear steam and water drum and the front mud-drum embedded in 85 the walls or setting, a circulating pipe or pipes connecting the rear one of the steam and water drums having their water-spaces in communication with the rear mud-drum placed inside the walls or setting, means for 90 introducing feed-water, and means for drawing off steam, substantially as described.

EDWARD R. STETTINIUS.
